UNITED STATES PATENT OFFICE.

HENRY B. COOLEY, OF NEW BRITAIN, CONNECTICUT, ASSIGNOR TO THE AMERICAN PAPER GOODS COMPANY, OF MONTCLAIR, NEW JERSEY, A CORPORATION OF NEW JERSEY.

MACHINE FOR AFFIXING FASTENINGS TO ENVELOPS.

1,233,194.

Specification of Letters Patent. Patented July 10, 1917.

Application filed December 30, 1912. Serial No. 739,214.

To all whom it may concern:

Be it known that I, HENRY B. COOLEY, a citizen of the United States, and a resident of New Britain, in the county of Hartford and State of Connecticut, have invented a new and Improved Machine for Affixing Fastenings to Envelops, of which the following is a specification.

My invention relates to machines for securing to envelopes the disks and cord that serve as a means for detachably securing the flap to the body of the envelop, and an object of my invention, among others, is to provide a machine of this class in the use of which the disks and cord may be securely fastened in a rapid manner.

One form of device embodying my invention and in the construction and use of which the object above set out, as well as others, may be attained, is illustrated in the accompanying drawings in which;

Figure 1 is a view in side elevation of a machine embodying my invention, part of the base being broken out.

Fig. 2 is a front view, scale enlarged, of the upper portion of my improved machine, the table being cut in vertical section on a plane passing through the groove for the disk carrier.

Fig. 3 is a side view of the same, looking in an opposite direction from the point of view of Fig. 1.

Fig. 4 is a detail view illustrating the construction of the disk carrier.

Fig. 5 is a detail side view illustrating the construction and operation of the cord carrying hook and knife.

Fig. 6 is a detail top view of the same.

In the accompanying drawings the letter B denotes the base of my improved machine that, as shown herein, is in the form of a column of suitable height to enable an operative to work standing up or seated on a high stool, and the letter F denotes the frame of the machine, of suitable form and construction to receive and support operative parts, which frame is secured to the upper end of the base and supported thereby. A fixed jaw 12 projects forwardly from the lower part of the frame and has an anvil 13 secured to its upper surface and a retaining pin 14 secured to and rising from the anvil, the latter supporting an envelop or flap thereof while the washer and string are being affixed.

A plunger 15 is mounted for vertical reciprocating movement in a head 16 of the frame, the lower end of the plunger having a hole within which a receiving pin 25 is yieldingly located to receive the hollow rivets or eyelets, by means of which the disks are secured in place, said pin being seated against a spring (not shown) in the bottom of the hole in the plunger, and the spring and pin being held in place in any suitable manner. A rock shaft 17 is mounted in the head 16, and links 18, 19 extending from said shaft and plunger respectively are pivotally secured to a plunger operating bar 20 that is pivotally connected with a bell crank lever 21, pivotally mounted at the upper part of the frame. A treadle 22 pivotally mounted in the base is connected by a rod 23 with the bell crank lever 21 as a means for operating the plunger. A chute 24 is located with its lower end at a distance from the anvil 13, and in position to deliver the eyelets or hollow rivets in the path of travel of the pin 25, by which, in the movement of the plunger, the eyelets are delivered on to the pin 14. The chute 24 is formed as an extension from a rocking hopper member 26 mounted on a shaft 27 extending from the frame. A rotating hopper member 28 is also supported on the shaft 27, the members 26 and 28 containing a chamber forming a hopper opening to the passage way in the chute 24. The member 26 is rocked in a well known manner by connection with the plunger and this moves the lower end of the chute out of the path of movement of the plunger at the proper time, and a ratchet mechanism 29 is employed to rotate the member 28 in a manner well known. A spring actuated holding bar 30 operates to retain the chute in its backward position away from the plunger until released at the proper time as by movement of the plunger. All the parts herein before described are of old and well known construction and further detailed description is therefore omitted herein.

In affixing disks to envelops by means heretofore employed, the rivets have been supplied and fastened by a machine similar to that herein above described, the disks having been manually placed in position in the machine, and the disks that secure the cord permanently having had such cord affixed thereto before the disks were separately

105

110

placed in the machine at each operation. By my improved machine, hereinafter described, the disks are automatically placed in position to be secured to the envelop and the cord is partially and automatically positioned and automatically secured in place, means being provided for severing the cord from a supply roll or like device, after such cord is secured in place.

In the device herein illustrated and embodying my invention, the numeral 31 denotes a disk magazine or tube in which disks 32 are located one upon another, the lower end of this tube resting upon a table 33. This table is secured to the frame F, projecting forwardly therefrom underneath the head 16, and a groove 34 is formed underneath the table to receive the edge of a disk carrier 35 pivotally secured to the underside of the table and having a slot to receive a stop pin 36 projecting from the underside of the table. This carrier has a lipped recess 37 into which and upon the lips of which the disks 32 move, one at a time, the distance between the upper surface of the lips and the upper surface of the carrier being substantially equal to the thickness of the disks. A carrier bar 38 is pivotally attached to the carrier (as shown herein) to a plate 39 rigidly secured to the carrier, and to a bell crank lever 40 pivotally mounted on the frame. This bell crank lever has a pin projecting into a slot 43 at one end of a carrier operating rod 41 and a spring 42 forces the pin to that end of the slot away from the connection of the rod with the bell crank lever 21, which connection is also by means of a pin on the lever engaging a slot 95 in the upper end of the rod 41, a spring 44 exerting force upon the rod in the same direction as the spring 42. This will cause the parts to assume the normal position shown in Fig. 1 in the drawings, with the recess 37 in the disk carrier underneath the plunger. A carrier holder 45 is pivotally mounted on the frame with its hooked end in position to engage a holding pin 46 rising from the carrier (as shown herein from the plate 39) when said carrier is at the backward limit of its movement, and retain it in this position until the holder is released by the movement of a holder releasing lever 47 pivotally mounted on the frame with one end in position to engage the holder and the other end in the path of movement of the pin 48 constituting the pivotal connection between the operating bar 20 and the bell crank lever 21.

A string controller disk 50 and a measuring disk 49 are rotatably mounted on the base B and are arranged to rotate together, the measuring disk being adapted to receive the string or twine 51 extending from a spool 52, or other source of supply, to the mechanism for utilizing the string. This

string will be so engaged with the measuring disk that its movement will be controlled by the said disk, in the structure herein shown the twine being wrapped one or more times about the disk, as may be desired. A pawl supporting arm 53, pivotally mounted, preferably on the stud supporting the controller and measuring disks, supports a stop pawl 54 and a disk moving pawl 55, the latter pawl being pivotally mounted on a finger 75 extending from the arm 53 and rigidly connected with the pawl 54. The moving pawl is arranged to engage a notch 56 in the controller disk and the stop pawl to engage a stop 57, herein shown projecting from the 80 edge of said disk. A spring 58 is employed to hold the disk moving pawl against the disk, and a pin 59 forming the pivot for the pawl 55 is extended into the path of movement of a cam 60 located at the end of a 85 swinging cam lever 61. This lever is pivotally supported on a movable part of the mechanism, as herein shown, on an actuating rod 62 connected with the string placing mechanism, and a spring 63 holds the cam 90 lever normally against a stop 64.

The actuating rod 62 extends from the treadle 22 to a string placing lever 65 pivotally secured underneath a flange 66 of the frame F. A cam post 67 is rigidly secured 95 to the lever and has at its upper end a hook actuating cam 68 located in position to engage a cam pin 69 projecting from the side of a string hook bar 70 bearing string hooks 71. The bar 70 is pivotally mounted at the 100 upper end of a bar supporting post 72 and on a rod 73 projecting therefrom, said post being pivotally supported by the lever 65 so that it may be rocked back and forth on said pivot. A knife 74 is secured at the end of 105 a knife support 75 pivotally mounted on a bracket 76 secured to the frame, this knife support having a stud 77 resting against the upper surface of the hooks and held against the hooks by a spring 78. A string bar actuating stud 79 projects from the side of the string hook bar into the path of movement of the back of the cam 68. A string guide 80 is secured to the bracket 76 and another string guide 81 is located on the opposite side of the jaw 12 from the first mentioned guide, the guide 81 having a notch 82 within which the string may be placed and from which it may be readily removed.

A string carrier 83 is carried at the end 112 of a string carrying arm 84, this carrier being tubular to receive the string and having an opening in which a string stop or detent 85 projects, this stop being in the form of a spring which will permit the string to 117 be carried forward but will prevent its backward movement. The carrier arm 84 is pivotally mounted on the bracket 76, as shown herein being secured to one end of a pivot mounted in the bracket, a block 86 being se- 123

cured to the opposite end of the pivot. A string carrier actuating rod 87 is pivotally attached at one end to said block and its opposite end is pivotally connected, by a pin and slot connection, with the bell crank lever 21, 88 being the pin and 89 the slot. A spring 90 holds the actuating rod 87 in its normal position, as shown in Fig. 3 of the drawings, and a string carrier stop 91 projects from the bracket 76 into the path of movement of the block 86 to define its normal position of rest.

The operation of the device is as follows:—An envelop or its flap is placed upon the anvil with the pin 14 projecting through the hole therein.

Before pressing downward upon the treadle, the operative grasps the end of the string projecting through the carrier 83 and extends it across the front of the machine, placing it in the notch 82 in the string guide 81 and extending it beyond the guide as far as permitted by the measuring device.

The parts being in the positions shown in the drawings, the treadle having been operated to move the lever 21 to carry the pin 48 to the bottom of the slot 95, a continued pressure upon the treadle 22 rocks the bell crank lever 21 further, actuating the plunger 15 through the medium of the links and bars 18, 19, and 20, starting the plunger in its downward movement.

The lower end of the chute 24 resting normally underneath the plunger, a hollow rivet 35 is in position to receive the pin 25, and the disk carrier 35 also resting normally underneath the plunger, a disk 32 is located in the path of movement of the pin 25.

As the plunger moves downward, the pin 25 passes into the hole in a rivet, immediately after which the chute 24 is moved from under the plunger in a manner common to prior machines. The continued movement of the plunger carries the hollow rivet through a positioned disk in the carrier 35, and before the shoulder at the base of the pin 25 strikes the disk, the carrier is moved backward from under the plunger, leaving the disk upon the rivet and the latter upon the pin.

In the operation of the carrier, it will be noted that the pin 48 moves in the slot 95 without moving the carrier, thus allowing the plunger to have an initial movement before the carrier is moved from underneath the plunger. When the pin 48 strikes the lower end of the slot 95, the operating rod 41 is moved downward against the tension of the spring 44, swinging the bell crank lever 40 on its pivot, the strength of the spring 42 being sufficient to cause this operation and to swing the carrier backward until the stop 36 engages the end of its slot. Expansion of the spring 42 will now permit the rod 41 to have a further movement, inde-

pendently of the carrier, this to permit movement of the plunger, if required, after engagement of the pin 36 with the end of its slot, when the carrier holder 45 engages the holding pin 46, retaining the carrier in this position for a limited time. In this position of the carrier the bottom disk 32 in the magazine 31 drops into the recess 37 ready to be moved forward by the carrier.

The movement of the treadle 22, as above described, operates, by means of the connecting rod 23, the string carrier actuating rod 87, the pin and slot connection 88, 89 permitting an initial movement of the plunger before operation of the string carrier. This operation of the rod 87 rocks the block 86 and the string carrying arm 84, and at the proper time the string, which has been extended across the front of the machine, is carried downward in close proximity to or against the front of the pin 14.

As the treadle is pushed downward carrying with it the actuating rod 62, the cam 60 strikes the pin 59 swinging the lever 61, tensioning the spring 63 and permitting the cam to pass the pin.

In this downward movement of the bar 62, as hereinbefore described, the cam 68 is swinging backwardly, permitting the string hooks to drop, under the influence of the knife support spring 78, in position to engage the string which has been extended, as hereinbefore described. The cam 68 in its continued movement strikes with its back against the string actuating bar stud 79 moving the supporting post 72 backward, carrying with it the string hooks 71 which, engaging the string, wrap it partially about the rivet under the washer. The continued movement of the plunger turns over the end of the rivet, in a manner well known, securing the washer and string firmly in place, the string between the washer and envelop. The backward movement of the hooks 71 carries the string against the knife, severing it from the length extending from the spool.

As pressure on the treadle is released the spring 92 carries the treadle upward reversing the movement of the parts.

As the bell crank lever 21 swings in the reverse direction, the springs 42 and 44 carry the lever 41 without movement of the bell crank 40, the slot and pin connection permitting this movement and thus allowing the carrier 35 to remain at the backward limit of its play for a certain period. As the bell crank lever 21 is thus moved backwardly the pin 48 strikes the releasing member 47, at about the completion of the movement of the bell crank lever, rocking the carrier holder 45, disengaging it from the pin 46 and permitting the carrier to swing to its normal position under the pull of the spring 44, a retainer 93 engaging the washer in the

carrier and preventing it being thrown therefrom as the carrier comes to a sudden stop.

In this reverse movement of the actuating rod 62, the cam post 67 is carried forward striking the cam pin 69 and raising the string hooks 71, after which the pin 69, striking the projection 94 at the upper end of the cam post, carries the hooks forward to their normal position of rest.

- 10 As the rod 62 moves upward the cam 60 engages the pin 59, and, being obliquely disposed with respect to its path of movement, swings the stop pawl on its pivot and carries its end out of the path of movement of the stop 57. The disk moving pawl will normally rest with its end a short distance from the shoulder formed by the notch 56, as shown in Fig. 1 of the drawings, so that the movement of the parts above described, and 15 sufficient to enable the stop pawl to be moved out of the path of movement of the stop, is permitted, and a continuation of the movement, caused by the cam 60, for a slight distance carries the stop 57 underneath the 20 end of the stop pawl 54 that now rests upon said stop. The measuring device is thus left, at the completion of an operation by the machine, in condition to permit the running out of the string to the proper length, the 25 controller disk, in this operation, making substantially a complete rotation, at the completion of which, the stop 57 engages the end of the pawl 54, that has resumed its location in the path of movement of the stop immediately upon disengagement of the cam 60 30 from the pin 59. The measuring disk 50 will be of a size to permit feed of the desired length of string in a single rotation of the measuring disk, which is permitted by 35 the construction of parts above described.

I claim—

1. A frame supporting a plunger with means for operating it and having means to support an article, means for supplying eyelets in position to be affixed to said article by said plunger, a carrier to supply disks to said plunger, means for retaining the carrier in a temporary position away from the plunger, means for releasing the carrier, and 45 means for moving it underneath the plunger.

2. A frame supporting a plunger with operating means therefor, a carrier to supply disks to said plunger, means exerting force 50 upon the carrier to normally press it toward the plunger, means for locking the carrier in a temporary position away from the plunger, means for releasing the lock to permit the carrier to be moved underneath the plunger, and means to support an article while being acted upon by said plunger to affix a disk to said article by means of an eyelet.

3. In combination with a plunger for affixing eyelets to an article, plunger operat-

ing means, a carrier to supply disks to the 65 plunger to be thereby affixed to the article by said eyelets, a rod forming part of a connection between the carrier and plunger operating means, a pin and slot connection between said rod and plunger operating means, a pin and slot connection between said rod and said carrier, and a spring for retaining the last mentioned pin in a predetermined position in said slot.

4. In combination with a plunger for affixing eyelets to an article, means for operating the plunger, a carrier movably mounted to supply disks to said plunger, to be thereby affixed to the article by said eyelets, a pivotally mounted lever connected with said carrier, an operating rod extending between said lever and plunger operating means, a pin and slot connection between said operating means and rod, a pin and slot connection between said rod and said lever, a spring 85 connecting said rod and lever to cause movement of the carrier, and a stop to determine the limit of movement of the carrier.

5. In combination with a plunger for affixing eyelets to an article, means for operating the plunger, a carrier pivoted for vibratory movement underneath the plunger, means for temporarily retaining the carrier in a position away from the plunger, operative connections between said carrier 90 and the plunger operating means, said connection including means to permit operation of the plunger operating means while the carrier is retained in its position from underneath the plunger, means for releasing said carrier, and means for moving the carrier underneath the plunger.

6. In combination with a plunger for affixing eyelets to an article, means for operating the plunger, a carrier for supplying disks to said plunger to be thereby affixed to the article by said eyelets, a stop to limit the movement of the carrier in one direction, means for retaining the carrier temporarily in a position from underneath the plunger, connections between the plunger operating means and said carrier including means to permit movement of the plunger independently of the carrier, and a spring 105 included in said connections and arranged 110 to be tensioned by said independent movement of the plunger, whereby force is obtained to return the carrier to its position underneath the plunger.

7. In combination with a plunger for affixing eyelets to an article, plunger operating means, a carrier for supplying disks underneath said plunger to be thereby affixed to the article by said eyelets, means for retaining the carrier in a position from underneath the plunger, a lever connected with the plunger operating means to operate said carrier, and a lever to release said 120 125

carrier holding means, said releasing lever being positioned for releasing movement by the plunger operating means.

8. A frame supporting a plunger with means for operating it and having means to support an article, means for supplying eyelets in position to be affixed to said article by said plunger, means for supporting a string normally out of the path of movement of the plunger and for changing the position of the string laterally into the path of movement of the plunger, other means for drawing the string laterally in the affixing operation, and means to affix the eyelet and string to an article.

9. A frame supporting a plunger with means for operating it and having means to support an article, means for supplying eyelets in position to be affixed to said article by said plunger, means for locating a string normally away from the plunger, means for moving the string laterally to a position near the plunger, and means for drawing the string laterally after it has been so placed to extend it partially around the plunger, whereby it is secured in the operation of fastening the eyelet to the article.

10. A frame supporting a plunger with means for operating it and having means to support an article, means for supplying eyelets in position to be affixed to said article by said plunger, means for supplying a disk to said plunger to be affixed to said article by said eyelet, for drawing a string up to the plunger and underneath the disk, and means for drawing the string into the space between said article and disk.

11. In combination with a plunger and means for operating it to affix an eyelet to an article, a guide for a string, a string positioning device located in line with the guide, means for moving said positioning device from said line, and means for drawing the string toward said plunger to be affixed by said eyelet.

12. In combination with a plunger and means for operating it to affix an eyelet to an article, means for positioning a string with respect to the plunger, to be secured to said article by said eyelet, a knife, a hook to draw the string toward the plunger, and means for operating the hook to draw the string against said knife.

13. In combination with a plunger and means for operating it to affix an eyelet to an article, means for positioning a string with respect to the plunger, to be secured to said article by said eyelet, a forked hook to engage the string, a knife located to project into said fork, and means for operating the hook to draw a string against said knife.

14. In combination with a plunger and means for operating it to affix an eyelet to an article, means for positioning a string with

respect to the plunger, to be secured to said article by said eyelet, a hook for drawing the string toward said plunger, means for operating the hook, and a knife held in yielding engagement with the hook in the path of movement of said string as it is drawn by said hook.

15. In combination with a plunger and means for operating it to affix an eyelet to an article, means for positioning a string with respect to the plunger to be secured to said article by said eyelet, a pivotally mounted hook, means for normally pressing the hook to engage the string, means for retaining the hook in a certain position, and means for releasing the retaining means to permit movement of the hook to position it to engage the string.

16. In combination with a plunger and means for operating it to affix an eyelet to an article, means for positioning a string with respect to said plunger to be secured to said article by said eyelet, a hook pivotally mounted, a cam to retain the hook in a certain position, means for operating the cam to permit movement of the hook to position it to engage the string and means for moving the hooks into engagement with the string.

17. In combination with a plunger and means for operating it to affix an eyelet to an article, means for positioning a string with respect to said plunger to be secured to said article by said eyelet, a hook pivotally mounted, means for retaining the hook in a certain position, and means for moving said retaining means to release the hook and to permit it to move pivotally to engage with a string, and means to operate the hook to draw it toward the plunger.

18. In combination with a plunger and means for operating it to affix an eyelet to an article, means for positioning a string with respect to said plunger to be secured to said article by said eyelet, a pivotally mounted string placing lever, means for operating said lever, a cam post secured to said lever, a bar supporting post also secured to said lever, and a string hook bar pivotally mounted on said bar supporting post and resting in engagement with said cam.

19. In combination with a plunger and means for operating it to affix an eyelet to an article, means for positioning a string with respect to said plunger to be secured to said article by said eyelet, a pivotally mounted hook, means for retaining the hook in a certain position and movable to release the hook and permit it to move pivotally to engage a string, means to draw the string toward the plunger, and means for operating said release and said hook operating means.

20. In combination with a plunger for

affixing a string to an article, means rotatably mounted and engaged by said string, means for stopping the rotation of said engaging means, and means connected with 5 said plunger for temporarily withdrawing said stop to permit rotation of the string engaging means.

21. In combination with a plunger for affixing a string to an article, means engaged 10 by said string to determine the length to be drawn out, a stop to determine such length, means connected with the plunger for temporarily withdrawing the stop, and means connected with the plunger for re- 15 placing the stop in position to prevent movement of said engaging means.

22. In combination with a device for affixing a string to an article, a drum about 20 which the string is wrapped, a pawl located to prevent movement of said drum but arranged to permit a slight movement of the drum, and means connected with said affixing device for moving said pawl from said position and for releasing the pawl to place 25 it in position to stop rotation of the drum.

23. In combination with a device for affixing a string to an article, a drum about which the string is wrapped, a stop connected with the drum, a stop pawl to engage 30 said stop, a releasing pawl connected with the stop pawl, and means operatively connected with said affixing device for operating the releasing pawl to temporarily remove the stop pawl from position to stop 35 the drum.

24. A frame supporting a plunger with means for operating it, means for supplying eyelets in a position in the path of movement of said plunger, a magazine containing 40 a quantity of disks, a carrier to convey the disks from said magazine to a position to receive said eyelets that are passed through said disks by said plunger, said carrier acting as a support for said disks when the eyelets are being passed through them and said 45 carrier having an opening to receive the

plunger, a slot extending from said opening to the edge of the carrier, means for removing the carrier from underneath the plunger after the affixing of the eyelets to the 50 disks, and means to support an article while being acted upon by said plunger to affix a disk to said article by means of an eyelet.

25. In combination with a plunger for affixing a string to an article, means for 55 positioning the string extending on opposite sides of a plane passing through the axis of the plunger, means for supplying disks to said plunger, means for drawing the string laterally and for wrapping it 60 partially around the plunger, and means for operating the plunger to secure the string between said disk and the article to which the disk is affixed.

26. In a machine of the class described, 65 the combination, with coöperating eyelet upsetting dies, a plunger by which one of said dies is carried, and means for operating said plunger, of means for feeding a washer and an eyelet into position in alinement with 70 said dies, means for feeding the end portion of a flexible fastening device approximately across the axis of said plunger in the space beneath the washer, and from side to side of the washer, whereby, upon the 75 upsetting of the eyelet, the fastening device is gripped throughout the full width of the washer between the washer and the material to which the washer is secured.

27. In a disk feeding machine, relatively 80 movable coöperating dies, an eyelet and washer feeding means, a string guide mounted to direct the end portion of a string between said dies to be clamped between a washer and the material to which the washer 85 is secured, means for moving the guide to position the string to be clamped, and means for severing the string.

HENRY B. COOLEY.
